UNITED STATES PATENT OFFICE.

MARTIN E. ANDERSON, OF DE KALB, ILLINOIS, ASSIGNOR TO JACOB HAISH COMPANY,
OF DE KALB, ILLINOIS.

TANK-HEATER.

1,268,202.

Specification of Letters Patent. Patented June 4, 1918.

Application filed April 6, 1917. Serial No. 160,141.

To all whom it may concern:

Be it known that I, MARTIN E. ANDERSON, a citizen of the United States, residing at De Kalb, in the county of Dekalb and State 5 of Illinois, have invented certain new and useful Improvements in Tank-Heaters, of which the following is a specification.

My invention has reference to tank heaters, of that class of such devices which are 10 designed to be partially submerged in a tank of water used as a supply for live stock.

One of the purposes of this invention is to provide a central fire-retaining chamber having removable parts spaced apart from 15 the outer shell of the heater, so that the water in the tank will at no time be in contact therewith, and in which the heater wall on the outside of the space will have no direct contact with the fire-box or heat 20 therein.

Another purpose of my invention is to have all of the interior parts of the device arranged and supported in such a way that they can be quickly removed from the heater 25 and replaced therein.

Still another purpose of the invention consists in the provision of parts whereby the character of the fire-box can be quickly changed so as to be suitable for the use of 30 coal or similar fuel, or for the burning of wood, cobs, or other light material.

Another advantage of my invention consists in conveying the current of heated air in an indirect manner, so as to produce a 35 considerable amount of radiation in the lower part of the receptacle, thus warming the water in the lower part of the tank, producing a more uniform temperature of the water throughout the entire tank.

These and other advantages of my device 40 will more fully appear from the following specification, reference being had to the drawings accompanying the same, in which:

Figure 1 is a vertical medial section of 45 my invention. Fig. 2 is a similar view with the interior parts removed. Fig. 3 is a similar view showing a modified construction and arrangement of the interior parts thereof. Fig. 4 is a plan view of the 50 grate 31.

The main part, or receptacle of my device, is adapted to be constructed of sheet metal, and is preferably, for convenience of construction, formed of two corresponding 55 parts, adapted to be rigidly fastened together. The drawings illustrate only one

of these parts, from the inner side thereof, with various supporting devices on the inner face thereof, and a reference to any of such devices will be understood to include 60 a corresponding part on the opposite wall of the receptacle.

My invention comprises a receptacle 1, provided with flanges 2, having openings 3 for use with bolts or other fastening means. 65 At its upper part the receptacle has a fuel and draft opening 4 and a flue 5 to which is attached a section of pipe 6, such pipe having an annular groove 7 engaging a bead 8 on the flue, providing a more rigid union 70 of such parts. Within the pipe 6 is a damper 9 of usual construction.

The device is provided with a central firebox, the rear part of which consists of several sections 10, removably supported by 75 ribs 11 on the wall of the receptacle 1, and provided with overlapping edges whereby a tight union is formed between the several sections. The ribs 11 are in form of a curve, and conform with the contour of that part 80 of the receptacle 1, a curved passage A being formed between such receptacle and the sections 10.

A grate 12 is supported on lugs 13 on the inner wall of the receptacle, such grate being in substantial alignment with the lower edge of the rear wall of the fire-box, and having at its forward edge a curved lip 14 upon which is loosely held a partition 15, the upper end of which is normally held 90 against the inner wall of the opening 4. The upper part of the fire-box has an opening which is normally closed by a plate 16, hingedly supported by means of trunnions (not shown) on the upper edge thereof 95 engaging hook shaped ribs 17 on the inner wall of the receptacle. The lower edge of the plate 16 is normally supported on a lip 18 of the upper plate 10, and held from upward movement by lugs 19 on the wall of 100 the receptacle. Said plate is capable of being moved upwardly in its support 17 and then dropped downwardly into the position shown in broken lines in Fig. 1, permitting a direct draft from the fire-box to the flue 5. 105

This feature would ordinarily be made use of when a fire was being started in the firebox, after which such plate would be closed. For convenience in handling said plate it is provided with an eye 20, readily engaged by 110 a poker or other tool. For the purpose of regulating said draft plate or providing

said fire-box with fuel, the partition 15 can be tipped forwardly into the position shown in broken lines in Fig. 1, but nothing is claimed broadly herein on this last-mentioned feature of the device.

A damper-plate 21 is held on supports 22 in the lower part of the receptacle, and adapted to be tipped forwardly for the purpose of removing the ash-pan 23, provided with a bail 24 for convenient manipulation.

The opening 4 is provided with a cover 25, centrally of which is a hood 26, having an opening 27 connecting through the hood with an opening 28 in the cover. By this means a current of air can be admitted to the receptacle without exposing the same to the entrance of rain or snow. Hinged in the upper part of the hood is a damper 29 provided with a toothed handle 30 adapted to engage the edge of a slot in the hood. By this means the opening 27 can be fully or partially closed, as desired.

When the interior parts of the device are in position, as shown in Fig. 1, and the fire-pot therein provided with a supply of fuel under combustion, a current of air passes downwardly through the front part of the receptacle, beneath the fire-box and upwardly through the passage A to the flue 5. Such portion of the air as does pass upwardly through the grate 12 is compelled to return downwardly through the same into the passage-way. The radiation is also increased by the curved rear portion of the receptacle adjacent to the passage A.

It is obvious that for the purpose of making repairs the sections 10 can be readily removed and replaced with other similar sections. The grate 12, partition 15, plate 16 and damper 21 can also be quickly removed, leaving the interior of the heater entirely clear, as shown in Fig. 2. The device is preferably formed throughout of metal, and can be cheaply constructed of cast-iron;

31 represents an auxiliary grate provided with trunnions 32 which are supported in bearings 33 on the wall of the receptacle 1, the forward end of such grate being held on lugs 34 on such wall. The forward part 50 of the grate 31 is turned upwardly and provided with a concave lip 35 upon which may be supported the partition 15, as shown in Fig. 3. By this means a much larger fire-box is produced, suitable for the burning of wood or other light material. In this use of the device the upper end of the partition 15 rests upon the wall of the opening 4, as before, and can be tipped rearwardly for the introduction of fuel. On the sides of the receptacle 1, in line with the lip 35, are bearings 36 upon which the partition 15 may be supported, if desired. A sufficient space is left between the grate 31 and front wall

of the heater for the circulation of the air, and when it is desired to remove the ash-pan, the partition 15 is first lifted out and the grate 31 tipped upwardly at its forward edge, into a vertical position. The grate 31 is provided with an eye 37 on its forward edge, by means of which it can be lifted out of the receptacle, when it is desired to discontinue its use.

What I claim as my invention, and desire to secure by Letters Patent of the United States, is:

1. A device of the class described, comprising a receptacle having an air inlet and an air outlet; a central fire-box comprising a rear wall, a grate adjacent thereto, and auxiliary grate adapted to be removably supported in said receptacle, and a front wall for said fire-box adapted for use with said first named grate or auxiliary grate,

2. In a device of the class described, a receptacle having an air inlet and air outlet; a central fire-box disposed to form a passage way from said air inlet to said air outlet and comprising a grate, an auxiliary grate adapted to be supported to form an extension of said first named grate, a rear wall spaced apart from the rear wall of said receptacle, and a front wall adapted for use with said first named grate alone or with both of said grates when used in conjunction.

3. In a device of the class described, a receptacle having an air inlet and air outlet, a grate mounted therein; and auxiliary grate adapted to be supported adjacent to the first named grate to form an extension in front thereof, said auxiliary grate being capable of being rocked upwardly into a position at right angles to said first named grate; a rear wall spaced apart from the rear wall of said receptacle, and a partition adaptable to the single or double use of said grates.

4. In a device of the class described, a receptacle having an air inlet and air outlet, and a fire-box centrally mounted therein, so as to provide a passage from said air inlet to said air outlet beneath said fire-box, and comprised of a grate, an auxiliary grate hingedly mounted at the front edge thereof, a rear wall formed of a plurality of sections, and a front wall adapted to be swingingly supported with relation to said first named grate or with reference to said auxiliary grate.

In testimony whereof I affix my signature in the presence of two witnesses,

MARTIN E. ANDERSON.
